SHOE HEEL

Ezequiel B. Cintron, New York, N. Y.

Application July 30, 1943, Serial No. 496,721

7 Claims. (Cl. 36—36)

This invention relates to heels for shoes and more particularly to replaceable inserts for both rubber and leather heels.

Applicant is aware that heels with replaceable inserts have been made but in such heels it has been very difficult to remove the damaged portion or insert of the heel, and the heel is often damaged in the removal thereof. Furthermore it has been very difficult for anyone not a shoemaker to either detach or attach such inserts. Also it has been very difficult for a person not skilled to properly position the insert with the remainder of the heel. In addition, it takes a skilled worker to fasten such inserts on to the heel.

It is an object of my invention to make it easy to detach the worn portion or insert of the heel without damaging the rest of the heel.

It is a further object to make it easy to attach a new insert.

Another object is to provide ready means for automatically guiding the insert into proper position on the heel with its wearing surface even with the wearing surface of the remainder of the heel.

Still another object is to provide means for securely fastening the insert on the heel without the use of tools.

These and other objects of the invention will be apparent from the description thereof to follow taken in connection with the accompanying drawing, in which—

Fig. 1 is a perspective view of one form of my improved heel attached to a shoe.

Fig. 2 is a bottom plan view of the improved heel of Fig. 1.

Fig. 3 is a bottom plan view of the replaceable insert removed from the rest of the heel.

Fig. 4 is a bottom plan view of the heel of Fig. 1 with the replaceable insert portion removed, and parts being broken away.

Fig. 5 is a cross sectional view of the replaceable insert taken on the plane of the line 5—5 of Fig. 3.

Fig. 6 is a cross sectional view taken on the plane of the line 6—6 of Fig. 4.

Fig. 7 is a plan view of a modified form of leather heel embodying my invention.

Fig. 8 is a plan view of the form of Fig. 7 with the replaceable insert removed.

Fig. 9 is a cross sectional view of a part of the heel of Fig. 7.

Referring to Figs. 1 to 6, inclusive, an ordinary shoe 10 is shown with an ordinary leather heel or lift 11. My improved rubber heel is mounted on the lift 11 and comprises a rubber body portion 12 of the usual standard size to fit the standard size heel or lift. It is preferable however that the body portion of the rubber heel be

slightly thicker than the ordinary rubber heel. This portion 12 is formed with a cut-away portion 13 resulting in a reduced portion 14 extending from substantially the center of the body portion 12 to its rear edge. The forward thickened portion of the body portion 12 has its rear wall 15 cut at a bevel or slant providing an overhanging edge 16, which edge may be reinforced by using harder rubber material at this point, or in any other suitable way.

The improved rubber heel is fastened to the lift 11 by nails or screws 17 driven through washer members 18 into the lift 11. The washer members 18 are joined together by metal strips 19 to which strips and washer members form a frame embedded in the body portion 12 and reduced portion 14.

On the reduced portion 14 of the rubber heel is an insert 20 of the same material and of the same shape as the cut-away portion. This insert is detachable and when in position its outer wearing surface is even or flush with the outer wearing surface of the thickened body portion 12. Its inner wall or edge 21 is beveled or cut on a slant to accommodate and fit the adjacent slanted inner wall 15 of the thickened body portion.

This detachable insert 20 is fastened to the reduced portion 14 by means of outwardly protruding spaced headless prongs or studs 22 adapted to be inserted into spaced openings 23 in the under surface of the insert 20. The studs 22 may have their surfaces roughened in order to more securely engage the walls of the openings 23. At about the center of the reduced portion 14 is a protruding stud 24 having a knob or enlarged portion at its top end. This stud 24 is adapted to be snapped into a metal snap fastener or socket member 25 on the under surface of the detachable insert 20. The studs 22 and 24 are connected to the metal frame formed by the strips 19 and with the washer members 18 form a unitary structure which holds the studs and washers rigidly in position.

In attaching the replaceable insert 20 on to the heel, its slanting edge wall 21 is placed against the slanting wall 15 of the thickened portion at which time the openings 23 in the insert will be directly over the studs 22 and the socket 25 will be directly over the stud 24. The insert is then pressed downwardly with the hand and the studs 22 will be driven into the openings 23 and socket 25 will be snapped over the knob of stud 24. These coacting studs, openings and socket will securely hold the replaceable insert on the rubber heel.

In order to detach the portion or insert 20 after it has been worn at the rear rim or for any other reason, a suitable tool is inserted underneath its inner surface at the rear edge. In

order to facilitate the reception of such a tool and to prevent damage to the adjacent surfaces of the thickened portion and of the replaceable insert, I have provided a metal strip or plate 26 suitably fastened to the outer surface of the reduced portion 14 at its rim. The detaching tool is inserted over the top of the plate 26 and the detachable insert 20 is lifted up and off of the heel.

The outer surface of the reduced portion 14 is provided with grooves 27 for coacting with grooved portions 28 on the inner surface of the detachable insert 20 in order to assist in securing the detachable portion and prevent squeaking of the heel. These grooved and ribbed surfaces are covered with a thin coating of rubber cement in order to assist the studs and sockets in holding the detachable insert on the heel.

In Figs. 7 to 9 is shown an improved leather heel with a replaceable insert. In this form, the heel 30 formed of leather has a thickened portion 31 and a reduced portion 32 of the same shape as the thickened portion 12 and reduced portion 14 of the form shown in Figs. 1 to 6, inclusive. In this leather heel, a reinforcing metal strip 33 is fastened on the top of the overhanging edge 34 of the thickened portion 31. In this form, the leather heel is fastened to the lift and sole of the shoe by nails 35 passing through the thickened portion 31 and nails 36 driven through the reduced portion 32.

The replaceable insert 37 is of the same shape as the replaceable insert or portion 20 of Fig. 1 and is fastened to the reduced portion 32 in the same manner as said insert 20 by means of the studs 22 and stud 24 engaging in openings 23 and socket 25, respectively.

This leather heel has no washer members 18 or strips 19 as in the case of the rubber heel of Fig. 1.

The coacting surfaces of the reduced portion 32 and replaceable insert 37 may be grooved and these surfaces are coated with rubber cement to insure the holding of the parts.

I claim:

1. A shoe heel comprising a permanent section provided with a cut-out portion extending from a point adjacent the front edge thereof along one side to a point rearwardly of the center thereof on its other side and a replaceable section in said cut-out portion and means for detachably fastening said replaceable section to the permanent section including roughened spaced studs and a headed stud protruding from said permanent section and coacting openings and a socket member carried by the replaceable section.

2. A rubber heel comprising a permanent section provided with a cut-out portion extending from a point adjacent the front edge thereof along one side to a point rearwardly of the center thereof on its other side and a replaceable section in said cut-out portion, means for fastening said sections to the lift of a shoe comprising a metal frame member embedded in said permanent section and means supported by said metal frame member for detachably fastening said replaceable section to the permanent section including roughened studs and a headed stud protruding from said permanent section and openings and a socket member carried by the replaceable section for coaction with said roughened studs and headed stud respectively.

3. A rubber heel comprising a permanent section provided with a cut-out portion extending

from a point adjacent the front edge thereof along one side to a point rearwardly of the center thereof on its other side and a replaceable section in said cut-out portion, means for detachably securing said replaceable section on said permanent section including roughened studs and a headed stud protruding from the permanent section and coacting openings and a socket member carried by the replaceable section and means on the permanent section for facilitating insertion of a detaching tool between the sections and for preventing damage to said sections when removing said replaceable section.

4. A rubber heel comprising a permanent section provided with a cut-out portion extending from a point adjacent the front edge thereof along one side to a point rearwardly of the center thereof on its other side and a replaceable section in said cut-out portion, means for detachably securing said replaceable section on said permanent section including roughened studs and a headed stud protruding from the permanent section and coacting openings and a socket member carried by the replaceable section and means on the permanent section for facilitating insertion of a detaching tool between the sections and for preventing damage to said sections when removing said replaceable section including a metal plate on the permanent section at its rim between the adjacent surfaces of said sections.

5. A shoe heel comprising a permanent section provided with a cut-out portion extending from a point adjacent the front edge thereof along one side to a point rearwardly of the center thereof on its other side and a replaceable section in said cut-out portion and means for detachably fastening said replaceable section to the permanent section including roughened spaced studs and a headed stud protruding from said permanent section and coacting openings and a socket member carried by the replaceable section, said sections having interfitting adjacent slanting edge walls for guiding said replaceable section into position on said permanent section.

6. A shoe heel comprising a permanent section and a replaceable section and means for detachably fastening said replaceable section to the permanent section including roughened spaced studs and a headed stud protruding from said permanent section and coacting openings and a socket member carried by the replaceable section, said sections having interfitting adjacent slanting edge walls for guiding said replaceable section into position on said permanent section, the upper surface of the overhanging edge of the slanting wall of the permanent section being reinforced.

7. A shoe heel comprising a permanent section provided with a cut-out portion extending from a point adjacent the front edge thereof along one side to a point rearwardly of the center thereof on its other side and a replaceable section in said cut-out portion, means for detachably fastening said replaceable section to the permanent section including roughened studs and a headed stud protruding from said permanent section and coacting openings and a socket member carried by the replaceable section, said sections having interfitting adjacent slanting walls for guiding said replaceable section into position on said permanent section, the adjacent surfaces of said sections being serrated for guiding the replaceable section into position on the permanent section.
